UNITED STATES PATENT OFFICE.

EDWARD L. WAIGHT, OF SAN FRANCISCO, CALIFORNIA.

SAFETY APPLIANCE FOR AIR-CRAFT.

1,103,233.

Specification of Letters Patent. Patented July 14, 1914.

Application filed April 17, 1911. Serial No. 621,727.

To all whom it may concern:

Be it known that I, EDWARD L. WAIGHT, a citizen of the United States, and resident of San Francisco, California, have invented 5 certain new and useful Improvements in Safety Appliances for Air-Craft, whereof the following is a specification.

My invention relates to the art of aerial navigation, and especially to devices in that 10 art for insuring a slow and safe descent, and a restoration to equilibrium, of air crafts, including aeroplanes, which from one cause or another, may have their buoyancy endangered.

15 The object of my invention is to provide in devices of the character described, novel means for automatically releasing and putting into operation the safety devices referred to, such as may be gas, compressed 20 air or other means wherewith quick action can be obtained, but for the purpose of this application I shall hereafter refer to explosive means, and with this object in mind my invention consists in combining with a 25 parachute case carried on and secured to an airship, explosive means for discharging the parachute therefrom into operative position.

It also consists in combining with a 30 parachute case carried on and secured to an airship, explosive means for discharging the parachute therefrom into operative position, and means for automatically producing the explosion at the required instant.

35 It also consists in combining with a parachute case carried on and secured to an airship, explosive means for discharging the 40 parachute therefrom into operative position, and electrical means for automatically producing the explosion at the required instant.

It also further consists in the novel parts, 45 combinations and arrangements described in the following description, shown in the accompanying four sheets of drawings, and particularly pointed out in the claims at the end hereof.

In the drawings, Figure 1, is a view in 50 elevation of a parachute as it appears in practice and a vertical section of the parachute case, attached to an airship, a portion only of the craft being shown. Fig. 2, is a vertical section of the case with the 55 parachute in elevation therein and the explosion chamber at the bottom thereof, also a dia-grammatical view of the means for auto-

matically exploding a charge in said chamber at the required moment. Fig. 3, is a central vertical section enlarged of the lower portion of the case and the parachute 60 therein, the explosion chamber with its electric exploders and the windlass for winding in the parachute rope, being shown in elevation. Fig. 4, is a central longitudinal section of the electric exploder. Figs. 5, 6 and 7 are detail views in section of the electric exploder. Fig. 8, is an elevation partly in section of the pendulum automatic switch for closing the exploder circuit.

The same numeral of reference denotes 70 the same part in whichever view it may appear.

In the drawings 1, is a case of suitable size for incasing a parachute 2 when the latter is folded after the manner of an umbrella, and said case is preferably of cylindrical shape. It is attached to an airship by suitable means, as the rods 3, and is provided with a windlass 4 for drawing in the 75 parachute rope 5.

On the bottom of the parachute at the point where the suspension cords 6 approximate one another is a piston 7, which fits the cylindrical case 1, and is drawn to a position near the bottom of said case, by 80 the windlass 4. Below said piston in its normal position is an explosion chamber 8; and in said explosion chamber is located a cartridge, or a plurality thereof as 9 and 10 as may be desired. The cartridges 85 contain explosive substances which evolve enormous quantities of gas under high pressure when exploded. Within said cartridges are arranged electric exploders 11, details of which are shown in Figs. 5, 6, 90 7; 12 being the head carrying the leading wires 13, 14; 15 being the electric fuse portion and 16 being the detonating portion. From the leads 13 and 14 extends an electric circuit including the wires 17 and 100 18, and the battery 19. Included also in said circuit are the means for automatically closing the same at the required instant, for discharging the cartridge aforesaid, which comprise the contact pendulum 20, electrically connected with wire 18 and the contact ring 21, electrically connected with wire 17. Pendulum 20, is suspended by ball and 105 socket joints 22 from the airship; and the ring 21 is rigidly suspended as by the rods 23 and 24, which are firmly fixed to the airship at the points 25 and 26.

Considering now the operation of my device as far as described. The pendulum naturally hangs in a vertical direction, and so long as the airship remains in or near a state of normal equilibrium, is out of contact with the contact ring 21. But supposing the airship should tilt; then some portion of the ring will come into contact with said pendulum thereby closing the circuit and exploding the cartridge which generates gas into the chamber 8 and shoots the piston outwardly in the cylinder and consequently forces the parachute out in an expanded form where it is held in an operative position by the end of the rope 5, which is secured to the windlass. Any force on the rope 5, as that produced by a falling airship further expands the parachute and causes the airship to fall slowly, at the same time tending to right it.

The righting tendency may be produced by securing the parachute to the top of the airship; or when several parachutes are used, to selected points along the sides.

I provide also means for adjusting my automatic contact device for any desired degree of tilting which consists in the sleeves 27 and 28 fixed to ring 21, and slidable over the sustaining rods 23 and 24, being fixed thereto in any desired position by the set screws 29 and 30, and for accurately adjusting the position of the ring, so that contact may be made at the instant when the airship has tilted any selected number of degrees, I provide the scales 31 and 32, fixed near and parallel to rods 23 and 24. The scales may be calibrated in any suitable manner, as for instance, a 45 degree mark at 33, 33', which would mean that if the ring were set on the rods at the point, the pendulum would make contact with the ring whenever the airship tilted 45 degrees. Corresponding marks are placed at proper distances above and below, and the position of the ring may thus be adjusted with accuracy to any degree of tilting which may be regarded as dangerous.

In case that for any reason the automatic pendulum switch should fail in its operation, I provide a hand-switch 34 which connects with wires 17 and 18 through wires 35 and 36, and which may be closed to fire the exploders at any time.

While I have indicated only a single parachute and case in the drawings, it is to be understood that my invention is not to be considered as limited to one alone, but that

I contemplate the use of one or any number thereof, attached to the airship in suitable positions, all, however, being arranged and operated substantially as shown.

My invention is especially adapted for use in aeroplanes wherein the danger from tilting is very great.

Having described my invention, what I claim as new and desire to secure by Letters Patent of the United States, modifications within the scope of the claims being expressly reserved, is:—

1. In a safety device for airships, a parachute case having an explosion chamber, explosive cartridges in said chamber, electric exploders in said cartridges, a ring adjacent to said cartridges and an electric circuit connected to said ring and said exploders.

2. In a safety device for airships, a parachute case having an explosion chamber, explosive cartridges in said chamber, electric exploders in said cartridges, an electrical contact pendulum, fixed electrical contact ring, a circuit between said electric exploders, said pendulum and said ring, closable by contact between said pendulum and said ring, and a battery in said circuit.

3. In a safety device for airships, a parachute case having an explosion chamber, explosive cartridges in said chamber, electric exploders in said cartridges, electrical contact pendulum, an electrical contact ring fixed to said airship and tiltable therewith, a circuit including a battery connecting said exploders, said pendulum and said ring, closable by contact between said pendulum and said ring, and means for adjusting the instant of contact to correspond with any selected degree of tilting.

4. In a safety device for airships, means for automatically closing an electrical parachute discharging explosion circuit, comprising an electrical contact ring connected in said circuit, fixed to said airship and tiltable therewith, and an electrical contact pendulum connected in said circuit and suspended inside said ring.

In testimony that I claim the foregoing I have hereto set my hand this 31st day of Mar. 1911, in the presence of witnesses.

EDWARD L. WAIGHT.
